UNITED STATES PATENT OFFICE.

FRANK W. HENRIKSON, OF MULBERRY, KANSAS.

COUPLING DEVICE FOR RAILWAY DRAFT CARS.

Application filed August 2, 1923. Serial No. 655,297.

This invention relates to coupling devices for railway draft cars, and more particularly to self-coupling devices for mine cars and the like.

- 5 In one of the ordinary types of coupling devices for mine cars, each car is provided with three links on one end of the draw bar and a hook on the other end. To couple this a man has to reach down for the 10 link and position it on the hook while the car is still in motion. Another type of coupler comprises three links and two hooks, with a hole in each end of the draw bar. In this form of apparatus, it is necessary to 15 position a hook in each end of the draw bar. Still another form comprises one link, a pin and a slot. The pin has to be lifted up by hand, the link pushed in the slot, and then the pin released.
- 20 In all these prior ways the coupling operations are very dangerous and are attendant with many accidents because the operator has to stand between the cars and couple them.

- 25 The present invention relates to a novel coupling mechanism which is constructed and arranged so that all coupling and uncoupling operations can be accomplished from the side of the car or from some equally safe position.

Still another feature of this invention is the provision of an effective self-coupling mechanism for use in connection with mine cars or the like, which coupling is capable of 35 considerable lateral swing in order to permit the mine cars to be drawn around the extraordinary sharp curves and bends so common in mine trackage.

- A further feature of the invention relates 40 to sides in the novel arrangement whereby the coupling mechanism is adapted either for the ordinary type of mine bottoms or for automatic mine bottoms. In automatic mine bottoms all loaded cars approach the shaft 45 from one and the same side of the shaft and the empties which have been hoisted, emptied and lowered are pushed or pumped away from the cage on the opposite side. The tracks for the loaded cars have a steep 50 grade approaching the cage, the rails on the cage are level, while the tracks leaving the cage on the empty side also have a steep grade inclined away from the cage. There 55 are automatic safety stops on the loaded tracks so that when the cage hits the bottom it automatically releases the dog on the

empty car on the cage and also the safety stop on the loaded car, which, standing on the steep incline, runs down onto the cage by gravity and pushes the empty off the cage onto the empty tracks on the opposite side of the cage. When the loaded car is thus positioned, on the cage in place of the former empty, it automatically dogs itself ready for hoisting. This is the well known 60 automatic bottom. Now in ordinary mines and slopes where they do not use gravity or automatic bottoms, the empty tracks and loaded tracks are always on opposite sides of the cage irrespective of the number of 65 tracks used; furthermore, the empties and loaded cars are pushed onto the cage by hand and all coupling and uncoupling is a manual operation.

The coupling mechanism disclosed in the 70 present invention is adaptable for both automatic and the ordinary type of mine bottoms—in that it is constructed so that the coupling can take place not only automatically self-coupling, and also by hand, but, 75 in addition, the mechanism can be set for non-coupling—that is, the cars will not couple when pushed together as ordinarily.

In automatic mine bottoms, a self-coupling car must be capable of being set so 80 that it is non-coupling. For instance, when the loaded car pushes the empty off the cage, there must be no coupling, otherwise when the cage is hoisted with the loaded car on it, the empty will hang down from 85 the side of the cage causing a wreck. In the present invention, the coupling mechanism is capable of being set for non-coupling so that, when desired, the collision of two cars 90 will not operate the coupling mechanism.

In this connection, another feature of the 95 invention resides in the means for automatically or manually re-setting the self-coupling mechanism, so that the car can self-couple, as desired.

These and other objects of the invention will be manifest from a perusal of the following specification when taken in connection with the accompanying drawings, where- 100 in:

Figure 1 is a side view partly in section of the mine car coupler;

Fig. 2 is a view on the line 2—2 thereof;

Fig. 3 is a plan view of Fig. 1;

Fig. 4 is an enlarged detail view of the 110 coupler with the mechanism set for automatic coupling;

Fig. 5 is a view on the line 5—5 of Fig. 4;
Fig. 6 is a perspective view of the latch or trigger operating levers and links.

Fig. 7 is a partly sectional view of the link ejecting mechanism; and

Fig. 8 is a similar view of the spring arrangement within the plunger for operating the link throw-out.

Referring now to the details of the invention, the mechanism is disclosed in connection with a standard type of railway mine car—obviously it has other applications.

In Fig. 1, the mine car 1 is of ordinary type. At the back end of it is provided with a coupling pin adapted to be passed through a link carried by the adjacent car to be coupled. The improved mechanism relates to the means for operating the pin. On its opposite end the car 1 is provided with my improved means for projecting the link outwardly so that a pin on the adjacent car can be passed therethrough for coupling. The pin operating mechanism will be first described in detail.

In one form of the invention, the end sill or bumper 2 of the car is recessed, as at 3, and the cap 4 on the end of the draw bar 5 is recessed, as at 6 and 7, to provide movement for the pin and its shifting mechanism. The pin is adapted to move vertically across the usual slot 7, adapted to receive the end of the link, shown as at 8 in dotted lines. The pin 9 is vertically passed through its registering slots 3 and 6 by means of a lever 10, having a forward toe 11 passing through an aperture 12 in the pin. The rear end of the lever 10 is pivoted, as at 13, between spaced supports 14 mounted on the upper portion of the cap 4. At an intermediate point 15, the lever 10 is provided with a connection to a lever lifting mechanism. For this purpose there is provided the pivoted loop 16 through which passes a pin lifter 17, preferably in the form of a horizontal rod journaled in the spaced back straps 18 and 19. The pin lifter has an intermediate crank 20, which is somewhat elongated to provide for a sliding movement of the lifter relatively to the loop 16. At each end the lifter is provided with crank handles 21 and 22 for manual operation of the lifter. The pin lever or carrier 10 is provided with a dog or trigger 23, pivoted thereto at 24. Between a toe 25 on the rearmost end of lever 10 and the dog 23 is arranged a coil spring 25 adapted to press the dog forward into locking position. For this purpose the dog is provided with a notch 26 which engages a stop 27.

With such an arrangement, when the crank 20 is angularly shifted to position shown in Figs. 4 and 5, the stirrup or loop 16 is likewise raised to swing lever or carrier 10 about its pivot 13, to thereby lift pin

9. At the same time dog 23 is arcuately swung upwardly so that the upper portion of notch 26 rests on stop 27. Spring 25 assists in this operation. In this position the pin is held in upper position and is ready for self-coupling. In self-coupling, when link 8 is projected against the dog or trigger 23, the dog is knocked off the ledge 27 and the carrier 10 is swung downwardly to pass the pin 9 through the link. Uncoupling is accomplished by again raising the carrier 10, as before. In the uncoupling operation, the spring 25 kicks the link out of the coupling recess 7. This is due to the fact that when the link presses the dog 23 rearwardly in the coupling operation, it puts spring 25 under compression, forcing lever 10 down. When lever is down compression of spring 25 is off. Raising lever 10 to raise pin 9 compresses spring 25 against dog 23 and kicks out link 8. When lever 10 is down the compression of spring 25 is off and when pin is raised spring 25 is compressed.

At times it is desirable to lock the pin in raised position so that automatic or self-coupling is impossible yet hand coupling can be done. And, preferably, it is desired to provide automatic means for releasing the pin from such a locked position. In one form of the invention this is accomplished by positively holding the pin upwardly so that, even when the dog 23 is actuated, no depression of the pin can take place. To this end, the link lifter 17 is arranged for horizontal sliding movement so that the crank arm 20 will be carried against the loop 16 and will pass or jam the lever 10 against the side of its support so that it is not free to move downwardly. This constitutes a very powerful and effective positive locking arrangement.

In order to automatically shift the pin lifter 17 sidewise, there is provided a link 28 pivoted to the backstrap 19 at 29. This link has upper and lower portions, the former having a slot 30 through which projects a laterally bent arm 31 of the pin lifter 17. The lower portion of link 28 is perforated to pivotally connect to a rod 32 having a crank 33 journaled, as at 34, on the side of the car. The other end of crank 33 is formed as an arm 35, adapted to be shifted outwardly by manual operation, or, if desired, automatically by a suitable dog or lug, and also to be shifted inwardly by a suitably located dog or lug. In Fig. 6, this latter dog 36 is shown in dotted lines. It is located at a desired point alongside the track, so that, as the car passes, the outwardly projecting arm 35 is pressed inwardly to set the safety lock for the pin lifter, so that automatic or self-coupling will take place when desired. If necessary, arm 35 can be moved inwardly at any time by manually shifting the pin lifter.

In the front end of the mine car is provided means for operating the link 8, so that it will be positively projected outwardly for automatically coupling and will be withdrawn into inward position after uncoupling so that no harm will be done to the link in the event of a collision. This construction provides a disappearing link. As illustrated clearly in Figs. 7 and 8, the draw bar 5, at the end opposite the pin lifting mechanism, is provided with spaced guides 36 for the link 8. These guides are preferably far enough apart to give considerable lateral movement to the link and further usual coupling pin hole 37 is also provided as an inner guide for the link.

The rear end of link 8 is provided with an arcuate slot or stirrup 38, into which loosely hooks an end 39 of a connecting rod 40. End 39 travels in a slot 41 in the draw-bar so that a straight line movement of the link is assured. The inner end of connecting rod 40 is pivoted, as at 42, to a crank 43, pivoted at 44. The opposite end of crank 43 has pivoted thereto an operating rod comprising a socket 45, pivoted, as at 46, to crank 43, an intermediate rod 47 and a second plunger socket 48. Socket 45 telescopingly receives an enlarged head 59 on the inner end of rod 47. Between this head and the inner end of socket 45 is a spring 50, adapted to be compressed when the rod 47 is pushed in. In normal position, shown in Fig. 8, the spring 50 exerts no tension. Rod 47 has loose thereon a collar 51, which lies snugly on the other side of cross bar 52, the draw bar 5 being channeled or grooved to receive the rod 47. A second spring 53 surrounds the outer end of rod 47, lying between the collar 51 and the inner end of a plunger socket 48. By this construction when the plunger 48 is pushed in the spring 53 is compressed and rod 47 is likewise pushed in to compress spring 50 until sufficient tension is reached to also push inwardly the socket 45 to actuate the crank 43, rod 40 and link 8, which is projected outwardly. By this construction, it will be noted that the connecting rod 47 is provided with a double spring adapted to operate the link mechanism when the plunger 48 is pushed in, yet in case the link misses the drawhead, the link will be forced back resiliently even though the plunger is in inward position. Spring 53 keeps the link retracted and spring 50 keeps the plunger projected.

By spacing the guide 36 a sufficient distance from the normal outward path of travel of the link and by providing the arcuate slotted connection between the link 8 and the rod 40, the link 8 is permitted to swing laterally to permit the coupling mechanism to effectively operate as the mine cars travel the sharp bends and returns so prevalent in mine trackage. A pin 54 passing

through hole 37 provides a guide for the inner walls of the link and permits the facile return of the link to disappearing position after it has been projected. This lateral movement of the link must be allowed for because all mine trucks are toward the center of the car and in taking short switches it is compelled to make very sharp curves which throws the end of the car, pulling the link on an angle of thirty-five to forty degrees, so that the end of the car is nearly over the rail. This is the reason that the link must have a circling movement. This construction also permits coupling on an angle.

In the operation of the above described coupling mechanism, it is to be observed that when two cars are bumped together, the plunger 48 is pressed inwardly against the tension of springs 50 and 53. As soon as spring 50 is compressed sufficiently, it forces socket 45 inwardly and shift arm 43 about pivot 44 and projects the link 8 outwardly along guides 36. If link 8 does not register with the link slot in the draw bar of the opposed car, then link 8 is harmlessly pressed inwardly against the tension of spring 50. On the other hand, if link 8 strikes the dog or trigger 23, the pin 9 being set in raised position, the link will actuate the trigger and drop the pin to complete the coupling. This is so provided the arm 35 has been shifted to an inward position. On the other hand, if the arm 35 is pressed out, which action will take place when the pin is normally lifted by operating the crank arm 21, the crank 20 of pin lifter 17 will be shifted to the left by the action of the arcuate slot 30 on the link 28, which lateral shifting of the crank 20 will press loop 16 sidewise and bind the lever 10 against the side of the support 14 to prevent its free movement. This is the locked position of the coupling mechanism—that is, it is non-coupling. If the link 8 strikes the dog 23 no movement of the pin 9 will take place.

However, if the arm 35 is now shifted manually inwardly, the pin lifter 17 will be shifted to the right to release the lever 10 for a subsequent coupling operation. However, if dog 23 is now struck by link 8, the pin will drop and self-coupling or automatic coupling takes place. On raising of the pin again the spring 25, which has been under tension, now acts to kick out the link as soon as the pin clears.

It is obvious that the mechanism herein set forth is but illustrative of the principles of the invention and is not to be construed as the only embodiment thereof. And it is not intended to restrict the invention except in so far as it is limited by the terms of the appended claims as interpreted by the disclosure of the prior art.

Having thus described my invention, what

I claim as new and desire to secure by Letters Patent, is:—

1. In a device of the class described, a drawhead adapted to receive the link of another car, a pin adapted to be shifted through such link, a member to shift said pin out of engagement with such link, a dog pivoted on said member and extending into the path of such link, said drawhead having means to support said dog and thereby said lever and link in shifted position, and a device to move said dog into and maintain it in supported relation with said drawhead means until operated by the link of another car during coupling.

2. In a device of the class described, a drawhead adapted to receive the link of another car, a pin adapted to be shifted through such link, a member to shift said pin out of engagement with such link, a dog pivoted to said member and extending into contact with such link when the latter is in engaging position, and a device to cause said dog to eject such link upon actuation of said member.

3. In a device of the class described, a drawhead adapted to receive the link of another car, a pin adapted to be shifted through such link, a member to shift said pin out of engagement with such link, a dog extending into contact with such link when the latter is in engaging position, a spring acting upon said dog to cause ejection of said link, and cooperating means upon said drawhead and said dog to prevent ejection of said link in the engaged position of said pin therein, said means permitting ejection of such links at actuation of said member to shift said pin.

4. In a device of the class described, a drawhead adapted to receive the link of another car, a pin adapted to be shifted through such link, a member to shift said pin out of engagement with such link, a dog extending into contact with such link when the latter is in engaging position, a spring acting upon said dog to cause ejection of said link, and cooperating means upon said drawhead and said dog to prevent ejection of said link in the engaged position of said pin therein, said means permitting ejection of such link at actuation of said member to shift the pin and thereafter holding said pin in its shifted position.

5. In a device of the class described, a drawhead adapted to receive the link of another car, a pin shiftable thereon, a lever pivoted at its rear portion to said drawhead

and connected at its front portion to said pin, a dog pivoted at a lower intermediate portion of said lever and extending into the path of such link, a loop connected to the upper intermediate portion of said lever, means to raise said loop to shift the pin in one direction, and means to hold the said dog, said lever and said pin in such shifted position, said means permitting the actuation of the dog by such link during coupling to allow shifting of the pin in the opposite direction.

6. In a device of the class described, a drawhead adapted to receive the link of another car, a pin shiftable through such link, a lever pivoted to said drawhead and connected to said pin, a dog pivoted to said lever, an abutment on said drawhead and a spring to force said dog against said abutment whereby said dog is guided for substantially rectilinear movement during actuation of said lever, an abutment on said dog in engagement with a first face on said abutment on said drawhead when said pin is in engaged position and with a second face of said abutment when said pin is in shifted position, means to move said lever to shift said pin, said dog being rocked upon engagement of such link in the drawhead to permit movement of its abutment into engagement with the first face of the drawhead abutment.

7. In a device of the class described, a pin, means to shift the pin to desired coupling and uncoupling positions, means to hold the pin in uncoupled position, devices to release said holding means and adapted to be actuated by the entry of the coupling link of another car into coupling position in said device, and a mechanism to prevent the release of said holding means in spite of actuation of said device when it is not desired to effect the coupling.

8. A device of the class described comprising a support, a pin shiftable to coupling and uncoupling position, a lever adapted to raise said pin, a dog disposed in the path of the coupling link of another car to hold said lever in raised position and adapted to be contacted by such link to release and permit the depression of said pin into coupling engagement with such link, and means for holding said lever against such depression.

In testimony whereof, I affix my signature.

FRANK W. HENRIKSON.
